FIG. 6

INVENTOR:

Erick Bernhard Peterson
by Chas. H. Luther
ATTORNEY

UNITED STATES PATENT OFFICE.

ERICK BERNHARD PETERSON, OF PROVIDENCE, RHODE ISLAND, ASSIGNOR TO GEORGE W. DOVER, INCORPORATED, OF PROVIDENCE, RHODE ISLAND, A CORPORATION OF RHODE ISLAND.

DIE.

1,281,649.

Specification of Letters Patent. Patented Oct. 15, 1918.

Application filed May 15, 1918. Serial No. 234,788.

To all whom it may concern:

Be it known that I, ERICK BERNHARD PETERSON, a subject of the King of Sweden, residing at Providence, in the county of Providence and State of Rhode Island, have invented a new and useful Improvement in Dies, of which the following is a specification.

My invention has reference to an improvement in dies and more particularly to an improvement in a form of a die adapted to split sheet metal, such as sheet metal blanks for false teeth backings and other forms of sheet metal blanks.

15 The object of my invention is to split a sheet metal blank through its thickness as the second step in forming up a comparatively large plate or backing integral with a pin on the backing.

20 A further object of my invention is to construct a die for splitting sheet metal blanks so that, by a comparatively slight change in one of its parts, it may be used for splitting sheet metal blanks of various 25 kinds and shapes.

Another object of my invention is to construct a splitting die so that a sheet metal blank is held on each side or surface, on a line with the splitting cutter, as the blank 30 is being split.

My invention consists in the peculiar and novel construction of a die for splitting sheet metal blanks, said die having details of construction, as will be more fully set 35 forth hereinafter and claimed.

Fig. 1 is a face view of my improved splitting die showing the same at the starting point of splitting a sheet metal blank.

Fig. 2 is an underneath view of the upper 40 die member showing the blank holding side bars partly broken away.

Fig. 3 is a vertical sectional view taken on line 3-3 of Fig. 1, with the die in the position, as shown in Fig. 1.

45 Fig. 4 is a detail transverse sectional view of the upper die member in a position for splitting a sheet metal blank.

Fig. 5 is a detail sectional view similar to Fig. 4 with the die in the closed position 50 and the sheet metal blank split down centrally a predetermined distance, and

Fig. 6 is an enlarged perspective view of a false tooth backing blank, after the same has been split in the die.

55 In the drawing 7 indicates my improved

die for splitting sheet metal blanks, 8 a sheet metal blank from which a false tooth backing is formed and 9 the blank after the same has been split in the die.

The die 7 consists broadly of a lower fixed die member 10 and an upper movable die member 11. The lower fixed die member 10 consists of a square base 12 supporting centrally a rigid vertical blank holder plate 13 of the same thickness as the sheet metal blank to be split. This blank holder plate 13 has the cut out and shaped opening 14 at its upper edge so as to hold a predetermined lower portion of the blank 8 as shown in Fig. 3. The upper die member 11 is shaped to correspond with the base 12 and has a stem on the top by which the die is secured in the press and a central opening 15 closed at the top 16 and sides 17, 17, and open at front and rear and on the bottom. A splitting cutter 18 having a concaved cutting edge 19 is held centrally and rigidly in place in the top of the opening 15 against the closed top 16 by two side clamping blocks 20, 20 which are placed at each side of the cutter 18. The cutter 18 and clamping blocks 20, 20 are held rigidly in place in the top of the opening 15 by bolts 21, 21, which are screw-threaded through the side of the upper die member 11 and engage with the adjacent clamping block 20. Each side clamping block 20 has a shallow recess 22 in its under side and opening into its inner edge, as shown in Fig. 2. Two blank holding side bars 23, 23 are shaped to fit in the recess 22 at each side of the blank holder plate 13 as shown in Fig. 1, and are held in frictional contact on the sides 17, 17 of the opening 15 by a U-shaped spring 24 operatively connected at each end to each bar 23, 23, as shown in Fig. 2.

When in operation, the upper die member 11 is raised so as to clear the blank holder plate 13 and a sheet metal blank 8 is placed in the opening 14 in the holder plate 13, that part of the blank to be split resting on the top of the holder plate 13, as shown in Fig. 3. The blank holding side bars 23, 23 are then placed in the recess 15 in the upper die member 11 at each side of the cutter 18 where they are frictionally held by the spring 24. The upper die member 11 is then lowered bringing the blank holding side bars 23, 23 down at each side of the blank 8 and holder plate 13 and the cut- 110

ting edge 19 of the splitting cutter 18 into engagement with the upper edge of the blank, as shown in Figs. 1, 3 and 4. The upper die member 11 is then forced down a predetermined distance and the cutter 18 splits the sheet metal blank 8 centrally and the ends of each split portion striking the bottom of the recesses 22, 22 in the side clamping block 20, 20, rolls over and outward, as shown in Fig. 5, thereby completing the second step in forming a false tooth backing from sheet metal as shown in Fig. 6. As the upper die member 11 comes down over the holder plate 13 the sheet metal blank 8 is held on each side, at the line of splitting, by the side blank holding bars 23, 23 which follow down with the upper die member 11 and cutter 18 until the split is completed. After the blank is split the upper die member 11 is raised, the blank holding side bars 23, 23 drawn out of the upper die member 11 and the split blank 8 removed from the holder plate 13.

It is evident that by changing the shape of the opening 14 in the holder plate 13, various forms of sheet metal blanks may be split, by the use of my improved splitting die.

Having thus described my invention I claim as new:

1. A die for splitting sheet metal blanks, comprising a fixed lower die member, a movable upper die member, a blank holding member in the form of a plate of the same thickness as the sheet metal blank to be split, on the lower die member, means for holding a sheet metal blank in the blank holding member, said upper die member having an opening, a splitting cutter in the opening, means for rigidly securing the splitting cutter in the opening in the upper die member, detachable means in the opening in the upper die member and moving synchronously with the upper die member, for holding the sides of the sheet metal blank, at the point of splitting, and which follows down with the point of splitting, as the sheet metal blank is being split down.

2. A die for splitting sheet metal blanks, comprising a fixed lower die member having a rigid blank holding plate the same thickness as the blank to be split, means for holding a sheet metal blank in the blank holding plate, an upper die member having an opening, a splitting cutter in the opening, means for rigidly securing the splitting cutter in the opening in the upper die member, detachable blank holding bars in the opening in the upper die member and moving synchronously with the upper die member, for hold-

ing the sides of the sheet metal blank, at the point of splitting and which follows down with the point of splitting, as the sheet metal blank is being split down.

3. A die for splitting sheet metal blanks, comprising a fixed lower die member having a rigid central blank holding plate the same thickness as the blank to be split, and having an opening in its top shaped to receive a sheet metal blank, an upper die member having an opening in its under face, a splitting cutter centrally in the opening, clamping blocks in the opening at each side of the splitting cutter, means for clamping the clamping blocks on to the splitting cutter to rigidly secure the splitting cutter in the upper die, detachable blank holding bars in the opening in the upper die member at each side of the blank holding plate, said blank holding bars fitting each side of the sheet metal blank and moving down synchronously with the upper die member, for holding the sides of the sheet metal blank, at the point of splitting, and which follows down with the point of splitting, as the sheet metal blank is being split down, and means for frictionally holding the blank holding bars in the opening in the upper die member.

4. A die for splitting sheet metal blanks, comprising a fixed lower die member having a central blank holding plate rigidly secured in a vertical position, and having the same thickness as the sheet metal blank to be split and an opening in its top shaped to receive and hold a sheet metal blank, an upper die member having an opening closed on the top and sides and open at each end and on the bottom, a splitting cutter in the opening and having a concaved cutting edge, a clamping block in the opening at each side of the splitting cutter, bolts screw-threaded through the die and engaging with an adjacent clamping block, detachable blank holding bars in the opening in the upper die member at each side of the blank holding plate, said blank holding bars fitting each side of the sheet metal blank and moving synchronously with the upper die member, for holding the sides of the sheet metal blank, at the point of splitting and which follows down with the point of splitting, as the sheet metal blank is being split down, and a spring operatively connecting the blank holding bars for frictionally holding the blank holding bars in the opening in the upper die member.

In testimony whereof, I have signed my name to this specification.

ERICK BERNHARD PETERSON.
